UNITED STATES PATENT OFFICE

EDWARD TINKHAM GIBSON, OF MIAMI, FLORIDA

MOTOR-CAR SIGNAL SWITCH

Application filed February 19, 1927. Serial No. 169,568.

This invention relates to motor-car signal switches adapted to be automatically and manually operated to electrically operate signals adapted to indicate that the moving car is about to turn to the right or to the left.

The object of my invention is to provide an improved plan of construction for a switch mechanism of this kind.

The object is accomplished by the switch mechanism illustrated in the accompanying drawings, in which

Figure 1 is a view from above of an embodiment of my invention.

In this figure the switch mechanism (without its cover member) is shown mounted on a fragment of the car's steering-post, and on a fragment of the hub of the car's steering-wheel.

Fig. 2 is an end view, looking forwardly, of the steering-post-supported member of the mechanism.

Fig. 3 is a side view of a vertical front to rear section of the mechanism shown in Fig. 1. The section is made through the dotted line 3—3 shown in Fig. 1.

Fig. 4 is a bottom view of the circuit-terminals of the steering-post-supported member, and its connection with circuits adapted to be electrified to electrically operate a direction-signaling device or lamp.

Fig. 5 is a perspective view of the steering-post-supported member covered by its cover-member.

Fig. 6 is a detail view showing the automatically-operable circuit-closing arm in operation.

Fig. 7 is a detail view showing the manually-operable circuit-closing piece in operation.

Fig. 8 is a view from above of another embodiment of my invention.

Fig. 9 is a perspective view of the bracket member of the mechanism.

Fig. 10 is a perspective view of a manually-operable circuit-closing piece made of spring metal.

Referring to the parts by numerals, 7 indicates a car's steering-post, and 8 indicates the hub of the steering-wheel. 2 indicates a bracket-member (Figs. 3 and 9) having a

bracket-plate section and adapted to be secured to the car's steering-post by a band 6. 10 is a bracket-supported part comprising a circuit-terminal-bearing member formed of insulating material mounted on a metallic base-plate 9 (Figs. 2 and 3) and having oppositely-disposed bench-sections 15 and 16 (Fig. 2). This member 11 is secured to the said bracket-plate section of the bracket 2 by means of two bolts 12 and 36 (Fig. 1) which pass through slots (see the slots 13 and 89 in Fig. 9, and the bolt 12 in the slot 13 in Fig. 3) in the said bracket-plate 3 to adapt the circuit-terminal-bearing member to be moved towards and from the steering-post to adjust it.

35 indicates a sleeve-shaft which is carried by and extends through the base of the said circuit-terminal-bearing member 11, and which has a head-rim 37 at its upper end and a nut 38 on its lower end. Mounted to turn to the right and to the left on said sleeve-shaft is an automatically-operable circuit-closing arm 34 having its rearward end section loosely projecting into a notch 39 formed in a hub-carried member 40 which latter is mounted on the lower end section of the hub 8 of the steering-wheel, and which is provided to automatically operate the said arm 34 when the steering-wheel is turned to an extent which causes the said arm 34 to leave the said notch 39 and ride on the periphery 41 (see Fig. 6) of the hub-carried member. The numeral 42 (see Fig. 3) indicates a wear-resisting metallic facing carried by insulating material disposed on the notch-engaging end of the said arm 34.

Carried by the forwardly-projecting end section 43 of the said arm 34 is a resilient contact-maker 44 adapted to be caused by the turning of the said arm to make contact with either one of two circuit-terminal pins 45 and 46 adapted to be connected to circuit-wires 25 and 28 respectively (see Fig. 4) which lead to the right and to the left chambers, respectively, of a direction-signaling lamp 26; and connected to the said sleeve-shaft 35 is a circuit-terminal 50 (Figs. 3 and 4) adapted to be connected to a wire 51 leading to the positive pole of a battery. To cause

the said arm 34 to bear resiliently on the periphery of the said hub-carried member 40 and spring back into its normal position when again opposite the notch 39, I provide a spring member 47 (Fig. 1) having legs 48 and 49 adapted to bear against the sides of the said arm 34 when the latter is turned out of its normal position.

Loosely mounted in the bore of the said sleeve-shaft 35 is a central-shaft 20 having its upper end disposed in a bearing-hole in a bearing-piece 70 and having on its upper end section a cam 67.

56 indicates a manually-operable circuit-closing piece which is pivoted midway between its extremities to turn on said central-shaft 20 in contact with the under surface of the said cam 67 (see Fig. 3), and which, when in its normal or non-operative position, 10 has the central long axis of the laterally-projecting sections 57 and 58 in a vertical plane at right angles with that of the central long axis of the said automatically-operable arm 34. Provided on the ends of the said piece 15 56 are downwardly-projecting protuberances 59 and 60 formed to sink into and frictionally engage upwardly-opening eyelet-hollows or 20 sockets 17, 18, and 19 disposed on the bench-section 15 of the circuit-terminal-bearing 25 member 11 at predetermined points in the path of the said protuberance 60, and with eyelet-hollows 21, 22, and 23 disposed on the bench-section 16 at predetermined points in the path of the said protuberance 59. To 30 cause the said protuberances 59 and 60 to snugly engage the co-operating eyelet-hollows so as to hold the manually-operable piece 56 against displacement therefrom by "joggling" 35 action of the moving car on the switch mechanism, a coiled spring 68 (see Fig. 3) is mounted on the lower end section of the central-shaft 20 between the under surface of the circuit-terminal-bearing member and a lock-nut 69 adapted to be suitably set to cause the said 40 spring 68 to draw the cam 67 into downwardly-directed pressure on the manually-operable piece (56). Disposed in the said eyelet-hollows 17 and 21 are circuit-terminals 24 and 27, respectively, which (see Fig. 4) are adapted 45 to be connected to the wires 25 and 28, respectively, which lead, respectively, to the left and right chambers of the direction-signaling lamp 26.

Rearwardly-projecting from the central section of the manually-operable circuit-closing piece 56 is a crank-arm 61 having a slot 62 engaging the downwardly-projecting section of a pin 63 (Figs. 1 and 3) carried by a push-rod 64 which is slidably mounted in 50 bearings 65 and 66 to provide means for manually operating the said circuit-closing piece 56. And projecting upwardly from the said push-rod 64 is the upper end section of the pin 63 (see Fig. 3) covered by insulating material 55 67 and engaging the slot 85 (Figs. 3 and

5) in the rear end section of an "action-indicator" arrow member 86 which is pivoted to turn on the upper surface of the cover-member 33 of the switch mechanism to indicate to the car driver the operative action that the manually-operable piece is performing and the consequent signal that the direction-signaling lamp is displaying.

52 and 53 are diminutive electric-light bulbs, mounted on the circuit terminal-bearing member (11) and disposed in its right and left electric circuits, respectively, to indicate to the car driver the condition of the circuits.

In the embodiment of my invention shown in Fig. 8 the numeral 80 indicates a base member formed of insulating material and bearing circuit terminals 78 and 79. The numeral 83 indicates a shaft supported by said member. Mounted to turn to the right and left on the central long axis of said shaft, and into and out of circuit-closing contact with said terminals 78 and 79, is an automatically-operable circuit-closing arm 75 carrying on the upper surface of its free end section an insulating piece 74. This arm 75 is adapted to be automatically operated when the base member 80 is positioned (not shown) to dispose the free end section of the arm within the notch in the hereinbefore described "hub-carried" member as is the free end section of the arm 34 in Fig. 1. The numeral 77 indicates a manually-operable circuit-closing piece which is mounted to turn on said shaft 83. This piece 77 has laterally-projecting sections (not indicated by characters) having their central long axes in vertical planes on opposite sides of and at angles with that of the central long axis of said arm 75. The numeral 81 indicates a crank-arm section of the piece 77. Attached to said crank-arm is a push-rod 82 adapted to be manually operated to turn the piece 77 into a position (not illustrated) wherein the downwardly-projecting formation on one of its said laterally-projecting sections makes circuit-closing contact with circuit-terminal 78 or 79. To automatically turn the said manually-operable piece 77 out of circuit-closing position and back into its normal one, the upwardly-projecting piece 74 on the arm 75 has its shaft-facing end 76 suitably shaped to adapt this end to abut against and engage such one of the said laterally-projecting sections of the piece 77 as is making circuit-closure and turn the said piece 77 when the said arm 75 is automatically turned into a position wherein the arm operates to cause closure of the same circuit. The shaft 83, arm 75, and piece 77 of the mechanism shown in Fig. 8 are to be connected to the positive pole of a battery. The said insulating piece 74 is provided to insulate the arm 75 from the "hub-carried member" of my switch mechanism.

In Figure 10 the numeral 90 indicates a

manually-operable circuit-closing piece pivoted midway between its ends to turn on the shaft 92 carried by the base 91, and having its end sections bent to provide downwardly-projecting formations 94 and 95 having their tips rounded to adapt the formations to sink into and detachably engage such upwardly-opening co-operating socket formations as may be (not shown) disposed on the base (91) in the paths of said formations 94 and 95. The said piece 90 in this Figure 10 is formed of slightly resilient metal to adapt it to cause the said formations 94 and 95 to bear resiliently against the base 91 when downwardly-directed pressure on the piece is exerted by the head 93 of the shaft 92.

In the embodiment of my invention illustrated in Figs. 1, 2, 3, 6 and 7, the numeral 71 indicates an upwardly-extending peg carried by and suitably positioned on the automatically-operable circuit-closing arm 34 to adapt the peg to abut against and engage a co-operating part (72 and 73 in Fig. 2 and 72 in Fig. 3) on the manually-operable circuit-closing piece 56 to turn the latter from a circuit-closing position (see 56 in Fig. 7) back into its normal or non-operative position (see 56 in Fig. 6) when the automatically-operable circuit-closing arm is turned from its normal or nonoperative position (see 34 in Fig. 7) to a circuit-closing position (see 34 in Fig. 6); in which latter position the said arm 34 causes its contact-maker 44 to make contact with a circuit-terminal (45 in Fig. 6).

What I claim is:

1. In a manually and automatically-operable switch for direction-signaling devices for automobiles, comprising a circuit-terminal-bearing member, a shaft supported by said member, and an automatically-operable circuit-closing arm mounted to turn on the central long axis of said shaft and operable by means carried by the steering gear of the automobile, the combination in the said switch mechanism of a manually-operable circuit-closing piece mounted to turn on the central long axis of said shaft; said manually-operable piece having laterally-projecting sections having their central long axes in vertical planes on opposite sides of and at angles with that of the central long axis of said automatically-operable arm; said arm carrying means adapted to abut against and engage either one of said laterally-projecting sections of said manually-operable piece to turn the said piece back into its normal position when the piece has been manually turned out of it into a circuit-closing position and the said arm is automatically turned into a position wherein the arm operates to cause closure of the same circuit.

2. A manually and automatically-operable switch mechanism for direction-signaling devices for automobiles, comprising a circuit-terminal-bearing member, a sleeve-shaft sup-

ported by said member, an automatically-operable circuit-closing arm mounted to turn to the right and left on said sleeve-shaft and operable by means carried by the steering-wheel of the automobile, a central shaft loosely mounted in the bore of said sleeve-shaft and provided with a cam or a head on its upper end section, a manually-operable circuit-closing piece mounted to turn to the right and left on said shaft and having laterally-projecting sections having the vertical planes of their central long axes on opposite sides of and at angles with that of the central long axis of said arm, each of said laterally-projecting sections having a downwardly-projecting formation fashioned to sink into and detachably engage co-operating socket formations disposed on the said circuit-terminal-bearing member in the paths of said downwardly-projecting formations at points coincident with the normal position and with the circuit-closing position of the manually-operable piece; said automatically-operable arm having a part adapted to abut against and engage a co-operating part on said manually-operable piece to turn the said piece back into its normal position when the piece has been manually turned out of it into a circuit-closing position and the said arm is automatically turned into a position wherein the arm operates to cause closure of the same circuit.

3. A manually and automatically-operable switch mechanism for direction-signaling devices for automobiles, comprising a circuit-terminal-bearing member bearing terminals of two electric circuits, an automatically-operable circuit-closing arm mounted to turn to the right and left on a vertical axis on said member into and out of closure of either one of said circuits and operable by means carried by the steering-wheel of the automobile, a manually-operable circuit-closing piece mounted to turn to the right and left on a vertical axis on said circuit-terminal-bearing member into and out of closure of either one of said circuits; said arm having a part adapted to abut against a co-operating part on said piece to cause turning of the said piece out of circuit-closing position and into its normal or non-operative position when the said piece is in a circuit-closing position and the said arm is turned to a position wherein it causes closure of the same circuit; said manually-operable piece having a downwardly-projecting formation fashioned to sink into and detachably engage co-operating socket formations disposed on the said circuit-terminal-bearing member in the path of said downwardly-projecting formation at points coincident with the normal position and with the circuit-closing position of the manually-operable piece.
